WORK WHEEL

Fritz E. Hendrickson, South Elgin, Ill., assignor
of forty per cent to Bror G. Olving, Elgin, Ill.

Application August 2, 1947, Serial No. 765,717

2 Claims. (Cl. 51—135)

1

My invention relates to polishing and buffing machines and more particularly to means for polishing and buffing articles of various kinds by the use of a polishing belt.

An object of my invention is to provide a work supporting pulley for a polishing belt of a more or less deformable nature, which is so constructed that it will be fully yieldable to give flexibility to the polishing belt at the point of polishing.

Another object of my invention is to provide a work-wheel that shall be well ventilated and tend to keep down the temperature of the work-wheel, the belt and of the work.

Another object of my invention is to provide a polishing and buffing machine having operatively associated therewith cooling fans to keep down the operating temperature of the work-wheel, belt and of the work.

Another object of my invention is to provide a perforated polishing belt.

Another object of my invention is to provide a work-wheel that shall be characterized by its ability to produce currents of cleaning and cooling air issuing from its peripheral surface and flowing through the polishing belt.

Still another object of my invention is to provide a relatively simple construction of buffing or polishing machine that shall be capable of providing a better polish than heretofore possible.

Other objects of my invention will either be apparent from a description of devices embodying my invention or will be pointed out in the course of such description and set forth in the appended claims.

In the drawings:

Figure 1 is a view in side elevation of one form of polishing machine embodying my invention,

Fig. 2 is a front elevational view of the apparatus shown in Fig. 1,

Fig. 3 is a sectional view of a polishing wheel taken on the line 3—3 of Fig. 14,

Fig. 4 is a plan view of a section of my work wheel,

Fig. 5 is a top plan view of the section of Fig. 4 partly folded,

Fig. 6 is a top plan view of a section completely folded,

Fig. 7 is a top plan view showing the section of Fig. 6 with the outer portions stitched together,

Fig. 8 is a view in side elevation of the section shown in Fig. 7,

Fig. 9 is a transverse sectional view taken on the line 9—9 of Fig. 4,

Fig. 10 is a sectional view taken on the line 10—10 of Fig. 5,

2

Fig. 11 is an end view of the section shown in Fig. 6.

Fig. 12 is a sectional view taken on the line 12—12 of Fig. 14,

Fig. 13 is a front elevational view of Fig. 14,

Fig. 14 is a side elevational view of a buffing wheel embodying my invention,

Fig. 15 is a fragmentary view of one form of perforated abrasive belt,

Fig. 16 is a side elevational view showing a modified form of buffing machine having air impellers mounted on the shaft of the work-wheel,

Fig. 17 is a front elevational view of the parts shown in Fig. 16,

Fig. 18 is a view, in side elevation, showing a still further modification using compressed air for cooling the polishing belt, the work-wheel and the work, and,

Fig. 19 is a fragmentary view of the surface of Fig. 3.

Referring first of all to Fig. 1 of the drawings, I have there shown a buffing or polishing machine designated generally by the numeral 21, which comprises a skeleton frame 23 which may comprise a plurality of angle bar members connected together to form a front support 24 and a horizontal support 25, which may be connected together as by struts 27.

I provide an electric motor 29 which may be supported on the horizontal platform 25 as by a base 31. While I have shown a specific form of base, I do not desire to be limited thereto and it is to be understood that means may be provided to permit of varying the position of electric motor 29 on the base in order to take up the belt.

I provide a pair of rotatable guide wheels 33 and 35 of which guide wheel 33 is fixedly supported as by a pair of bearing brackets 37, the wheel of pulley 33 being mounted on a shaft 39.

The pulley 35 is supported by a short shaft 41 which is supported by a double lever arm 43 which is pivotally supported on a fixed shaft 45 supported by one of the front angle bars 24. A coil spring 47 is connected to the inner end of one arm of lever arm 43 while the other end of spring 47 is connected with a fixed pin 49, which may be mounted on and secured to strut 27.

A work-wheel 51 is mounted on a shaft 53, which shaft is supported by a pair of bearing brackets 55 supported on the two front vertical members 24 and is positioned between guide pulleys 33 and 35. An abrasive or polishing belt 57 is adapted to be driven by a pulley 59 mounted on the shaft of motor 29 and extends around the

two guide pulleys 33 and 35 as well as the work-wheel 51.

I do not desire to be limited to the positions of the various parts of the machine shown in Fig. 1, since other positions may be occupied by the various parts.

Referring now to Figs. 3 to 14 inclusive, I have there shown one form of work wheel which may be constructed as follows. I provide a plurality of individual flexible plies 60 of cloth and of a substantially circular or oval shape, each ply being provided with a central opening 61 extending along the longer diameter of the plies. I may use from five to ten plies of cotton cloth. I provide further a plurality of seams 63 extending across the set of plies and while I have shown a specific location for the individual seams I do not desire to be limited thereto since minor changes may be made in the location of the seams and still obtain the desired results. I provide an additional or strengthening member 65 which may be made of heavier cloth than are the plies 60, such as heavy duck, and hold the same in place as by a pair of longitudinally extending seams 67.

Each set of plies 60 are then folded along a median line 69 when the plies 60 will have the shape as shown in Fig. 5 of the drawings. I then take and fold inwardly the intermediate parts of the end portions of the plies 60 until they occupy a position substantially as shown in Fig. 6 of the drawings. I then provide seams 71, one adjacent each of the return or inwardly-bent end portions so that the shape of the set of plies 60 is as shown in Fig. 7.

I then mount, say, six sections of plies 60, folded as shown in Figs. 7 and 8, on a pair of hooks 73, which may be integral with metallic discs 75 and 77. Each of said discs is provided with a plurality of hook-shaped ends 73 which are bent out of the plane of the discs 75 and 77 so that when the sections 60 have been mounted in proper operative positions on said pairs of hooks 73, the hooks may be forced apart from each other peripherally, the hook ends overhanging the walls of opening 61 so that each of the sections will be held in proper operative and desired positions on the discs 75 and 77, which discs are adapted to be mounted on a drive shaft 79, (Fig. 3). I may also mount the sections when folded as shown in Figs. 5 and 10, and find that the flexible plies will take the shape shown in Fig. 19, there being a small space between each two adjacent sides of the sections as indicated by 89 in Figs. 3 and 19.

This drive shaft 79 is provided with an inner clamping disc 81 and spacing members 83 are placed between each two adjacent pairs of discs 75 and 77 having mounted thereon the sections 60. An outer clamping disc 85 is held in tightly clamping position as by a nut 87 having screw-threaded engagement with the outer screw-threaded end of shaft 79.

The outside discs 81 and 85 may have air inlet openings 86 provided therein, while the discs 75 and 77 may also have openings therein to permit distribution of air to all channels 80 between the various sections. This will allow a large volume of air to be moved through said channels and to issue from the multitude of openings in the circumferential face of the work wheel.

The construction of my improved work wheel is preferably such that it has some inherent stability when not rotating, which increases when

in rotation. I have found that belt supporting work wheels heretofore used permit the belt to leave it as soon as the belt is started, but with my improved work wheel the belt will not run off the work wheel when being started.

Referring now to Fig. 18 of the drawings I have there shown a work wheel 51 and two guide pulleys 33 and 35 with a motor-driven polishing belt 57 passing thereover. I have further shown 10 two air supply ducts 89 and 91 which are so positioned that air flowing through duct 89 will impinge on the outer surface of work-supporting wheel 51, striking the outer surface of wheel 51 just before it meets with the belt 57. The air 15 from duct or pipe 91 is adapted to meet the outer surface of belt 57 just at the point where a piece of work 93 is held against belt 57. The pipes or ducts 89 and 91 may be provided with cold air from any suitable source and at any suitable 20 pressure. The air from duct 89 may also impinge against the inside surface of belt 57.

Referring now to Figs. 16 and 17 I have there shown an abrasive belt 57 driven by a motor 29, the belt running over pulleys 33 and 35 as well 25 as over a work wheel 51. I have further shown that the work wheel 51 is mounted on a shaft 95, supported as by a plurality of bearing brackets 97, there being air impellers mounted on the outer end portions of shaft 95. One air impeller 30 99 is adapted to force air against the outer surface of belt 57 through a bent conduit 100 while the second impeller 101 is adapted to force air against the inner surface of the belt through a bent conduit 102, impeller 99 therefore doing substantially 35 the same thing as is done by pipe 91 while impeller 101 does substantially the same thing as is done by pipe 89. Air impellers 99 and 101 are provided with air-moving blades 103 or by any other suitable means for forcing air to enter the 40 impellers in an axially inwardly extending duct and is then forced out of the pipes shown in Figs. 16 and 17.

Fig. 15 shows one form which the abrasive belt 57 may take. As shown in Fig. 15, this belt 45 105 is provided with a plurality of relatively small openings 107. These openings 107 will have the effect of permitting air from, say, pipe 89 or from impeller 101 to strike the periphery of work wheel 51 and the inner surface of belt 105 and 50 then to permit a part of the air to flow outwardly through the openings 107 in the belt. The air flowing through pipe 91 or through impeller 99 will do the same except that it will flow inwardly through the openings 107.

55 I have found by tests on work wheels constructed as shown in Figs. 4 to 14 inclusive that they have several important advantages over wheels used at present in the art. One of these 60 advantages is that the wheel is inherently self-ventilating and that therefore the temperature at which it operates will be much lower than is the case at present. Fig. 19 shows the shape which will be assumed by the outer part of the sections when running at operative speed where 65 the sections are subject to centrifugal force. It is evident that there will be spaces between the sides of adjacent sections with the cooling air flowing radially outwardly because of the fan action of the parts of the sections extending 70 axially of the wheel. This cooling air will also clean the polishing belt as well as the work wheel sections, since it is drawn from the space surrounding the work wheel and forced therethrough. This has the effect of giving a longer life to the work wheel than would otherwise be

the case, as well as maintaining the temperature of the work at a much lower value than with other work wheels now in use.

I have said that it is advisable that all the cloth segments have some inherent stability when at rest and since they are subjected to centrifugal force when running, this stability is greatly increased when the work wheel is rotated. I further make the length of the hook portions 73 greater than the thickness of the plies so that the plies 51 may be forced inwardly against the outer peripheral part of discs 15 and 77 while the machine is at rest by the pressure of the belt 57 against the sections 60 during the slowing down of the wheel but will be forced outwardly against the adjustable belt 57 while in operation. I have found that it is best to provide the work wheel with a certain amount of inherent stability, this inherent stability of the work wheel being of great advantage in holding the belt on the work wheel.

As a result of work with and on my invention I have found that the soft backing provided by the work wheel results in a finer finish on any kind of metal which is polished by a machine embodying my invention. Generally speaking a softer backing for a polishing belt gives a finer finish. The construction of the work wheel and particularly of the individual sections, so that each individual section will have a softer intermediate portion and two relatively harder end portions, tends to provide the belt with a soft backing.

The fact that the hook members 73 on discs 15 and 77 are longer than the thickness of the assembled plies 60 permits of radial movement of the plies, outwardly under the influence of centrifugal force and radially inwardly when it is not operating and particularly when said belt is subject to pressure from a piece of work 93 being polished. The operator is able to detect a whipping action or movement beneath the belt and the fact of the variation of softness of each individual section, as well as the looseness of mounting of each section on the hooks is, in my opinion, the explanation.

I have found that with a polishing wheel it is possible to press a piece of work, such as a thin sheet of metal, against a wheel so that the work will become discolored because of excessive friction. When using my improved work wheel I am of the opinion that the flow of cooling air is substantially that shown by the curved lines 109 in Fig. 12, the air entering at points 111 of Fig. 14 and then flowing out radially as shown by lines 109 of Fig. 12. If now there is added the forced ventilation shown in Figs. 16, 17 and 18, the temperature of all of the parts is maintained at a relatively low value which helps to cause a high polish on the work.

Although I have described one form of self-ventilated work wheel, I do not desire to be lim-

ited thereto as the machine will work satisfactorily and produce a superior finish when using any type of self-ventilated and self cooling work wheel capable of producing the required cooling of the belt and of the work.

This application is a continuation-in-part of my application Ser. No. 657,804, filed March 28, 1946, now abandoned.

Various modifications may be made in the device embodied in my application without departing from the spirit and scope thereof and all such modifications coming clearly within the appended claims may be considered a part of my invention.

15 I claim as my invention:

1. A polishing machine comprising an endless polishing belt, a pair of pulleys around which said belt passes, a self-ventilated belt-backing work wheel comprising a solid central portion and a flexible outer portion, air impellers secured one to each side of said solid central portion and air outlet means for said impellers for forcing cooling air into the contact area between the work and the polishing belt and between the polishing belt and the workwheel.

2. A polishing machine comprising an endless polishing belt, a plurality of pulleys around which said belt passes, one of said pulleys constituting a belt-backing workwheel and having therein air-entrance openings near the hub and internal passages extending therefrom to the circumferential surface for conducting air to the circumferential surface and to the belt, said belt having openings therethrough to permit air to pass therethrough to a work piece applied to said belt, whereby such air may cool said wheel, said belt, and the work piece.

FRITZ E. HENDRICKSON.
